UNITED STATES PATENT OFFICE.

OLIVER C. KNIFE, OF PALO ALTO, CALIFORNIA.

RECOVERING GOLD AND APPARATUS THEREFOR.

1,426,746.

Specification of Letters Patent. Patented Aug. 22, 1922.

Application filed October 31, 1921. Serial No. 511,692.

To all whom it may concern:

Be it known that I, OLIVER C. KNIFE, a citizen of the United States, residing at Palo Alto, in the county of Santa Clara and State of California, have invented new and useful Improvements in Recovering Gold and Apparatus Therefor, of which the following is a specification.

This invention relates to a process and apparatus for treating insoluble finely divided matter carried in a finely divided or colloidal condition in any menstruum in which it may be suspended or dissolved, and particularly to such process and apparatus as may be employed in connection with the abstraction of gold from a muddy watery menstruum which carries it in a finely divided condition. In the recovery of gold as now practiced the ground rock or alluvial matter carrying the gold is agitated in the presence of mercury by which much of the valuable mineral is extracted and then is treated in chemical ways as by cyanide process or other similar treatment to extract as nearly as possible all of the valuable material. With all of the refined conditions at present in practice there is still about two to four per cent gold which is not recovered. It is the object of my invention to recover a considerable portion of this residue.

In carrying out my invention I take the muddy water which is carried in suspension together with the gold and subject it to rapid rotation in a partially closed flanged drum and feed the muddy gold-bearing solution to the interior of the drum, spreading it in a series of fine jets or spray against a drum lining, one surface of which is coated or partially impregnated with a substance which will have a chemical or mechanical affinity for gold. Under the centrifugal thrust the heavier particles contained in the solution are projected against the coated lining and retained thereby and after a period of operations practically all of the insoluble material will be deposited in the form of a more or less deep film and the supernatent clean water may be carried out to a drain by suction or an overflow.

My invention therefore consists of a method of recovering valuable insoluble matter carried in a desired medium by rapidly rotating it in a closed chamber and affixing it to the walls thereof and withdrawing the fluid medium. It consists also of an apparatus comprising a rotating drum, means for

projecting a divided stream of gold-bearing solution to the interior of the drum, means for trapping the gold and insoluble material and means for removing the supernatent water. It comprises other features more specific which will be hereinafter more fully described and will be definitely indicated in the accompanying claims.

In the accompanying drawing illustrating the invention:

Figure 1 is a sectional elevation of an apparatus embodying my invention.

1 represents a sheet iron drum open with a wide diameter at its outer end and mounted in a rigid substantial trunnion at the other end mounted in a standard 2 and rotated at high speed from any suitable source of power by drive pulley 3. On the inner wall of the drum is applied a cup-shaped lining 4. I preferably make this of some moderately porous material such as paper which may be readily collapsed so that it may be introduced into the interior of the drum and form a snug lining. I preferably apply a stiff grease to the inner wall of the drum. Under the rapid rotation of the drum the liquid carrying the gold fed from a supply pipe 5 through a reticulated mouth 6 is held in the form of an annular cylinder and the heavier particles driven toward the walls and settle upon the paper lining, combining in a cohesive way either chemically or mechanically with the greased surface. After a short interval of time the insoluble portions of the fluid medium fed to the drum will be practically all extracted. The heavier particles, as gold, being closest to the greasy surface of the paper and the rocky matter lying on top, whereas above will lie a considerable depth of clean water which may be withdrawn by a suction through a pipe 7, the suction being controlled by a cock 8. I preferably insert in advance of the cock a pet cock 9 by which the operator may easily ascertain when the operation has been carried on sufficiently to extract all the insoluble material, as by opening the latter the drip will instantly indicate to him as to the clearness or cloudiness of the liquid how nearly completed the operation has been carried on.

I may use further aid to the extraction of the gold the use of mercury, which may be operated conjointly with the means already described. To this end I apply a rose jet 10 in the mouth of the supply pipe leading by

pipe connection of sufficient length as indicated at 11 by which a bottle of mercury may be employed to feed to the drum.

After a sufficiently deep bed of solid residue has been extracted, the flexible lining with the valuable charge is removed from the drum and treated by heat to volatilize the grease or mercury or both and burn out the paper leaving within the muffle an ingot 10 of pure gold from which the silicious matter may be skimmed or.

Having thus described my invention, what I claim as new and desire to secure by Letters Patent, is:

- 15 1. The process of recovering finely divided insoluble material in dilute suspension in a liquid consisting in rapidly rotating the liquid in a hollow open drum, a lining of porous fabric on the inside of the drum coated with grease to imbed and retain the gold, and simultaneously removing the clear water after a sufficient period of centrifugal action.
- 20 2. A centrifugal separator for recovering gold and accompanying insoluble materials from dilute colloidal solutions thereof comprising a rotary hollow flanged drum, a lin-

ing of porous structural material therefor coated with a film of grease and mercury for seizing the gold, a feed pipe to supply the 30 gold-bearing solution, and means for automatically withdrawing the clear water.

3. The process of extracting gold from a menstruum carrying the same in suspension consisting in feeding the menstruum to a 35 centrifugally operated drum lined with a porous fabric, and simultaneously spraying finely divided mercury to the interior of the drum.

4. Means for extracting gold from liquid 40 solutions in which it is carried by suspension, comprising a rotary drum, a lining therefor, carrying a film of a greasy substance having attraction for gold, an induction pipe for supplying the liquid to the interior of the drum, a suction for withdrawing the clear water, a valve controlling the suction, and a pet cock between the valve and the drum for ascertaining the condition of the extraction.

In testimony whereof I hereunto sign my name.

OLIVER C. KNIPE.
